INFLATING DEVICE

Walter H. Freygang, Essex Fells, N. J., assignor
to Kidde Manufacturing Co., Inc., a corporation
of Delaware

Application January 28, 1944, Serial No. 520,125

16 Claims. (Cl. 9—2)

The present invention relates to inflating means of the type employing stored high pressure fluid medium for inflating or distending devices subject to effects from water or other liquid, such as life-vests or belts for individual use, life-boats or rafts for the use of one or more persons, and flotation bags of the character utilized for preventing the sinking of aircraft when the latter are not otherwise in condition to float upon a body of water.

One of the principal objects of the invention is to provide an inflating device so constructed and arranged whereby a desirable proportion of air from the atmosphere may be mixed with stored high pressure fluid medium for inflating a flotation device in order to reduce the quantity of the medium and the size and weight of its container with relation to the quantity of the medium and size and weight of the container heretofore required for inflating similar flotation devices, thus, making it possible to equip flotation devices with smaller and lighter containers and, if desired, to conserve a quantity of the inflating medium for future use.

Another object of the invention is to provide an inflating device of the foregoing described character equipped with means for insuring inflation of the flotation device in instances where the air is not available due to the submerged condition of the means through which the air is supplied.

A further object of the invention is to provide selector means operable by a fluid medium for selecting a predetermined type of fluid medium for mixture with the operating fluid medium and for precluding the mixture of the operating fluid medium with an undesired type of fluid medium.

A still further object of the invention is to provide an inflating device of the foregoing described character which is simple in construction, durable in use, efficient in operation, economical in manufacture, easy of assembly, readily substitutable for devices not having its novel attributes, and which lends itself to mass production.

Other and further objects of the invention will be obvious upon an understanding of the illustrative embodiments about to be described, or will be indicated in the appended claims, and various advantages not referred to herein will occur to one skilled in the art upon employment of the invention in practice.

Embodiments of the invention have been chosen for purposes of illustration and description and are shown in the accompanying drawings, forming a part of the specification, wherein:

Figure 1 is a top plan view of a life raft in

inflated condition and equipped with an inflating device, illustrating an embodiment of the invention.

Figure 2 is a longitudinal sectional view of an injector associated with the inflating device.

Figure 3 is a cross sectional view, on an enlarged scale, taken on the line 3—3 of Figure 2, illustrating a fluid selector valve.

Figure 4 is a sectional view taken on the line 10 4—4 of Figure 3, with the valve members in closed position.

Figure 5 is a view similar to Figure 4 but illustrating the valve members in open or outer positions.

Figure 6 is a longitudinal section of a modified form of the injector.

Figure 7 is a longitudinal section of another modified form of the injector.

In practising the invention, as illustrated in Figures 1 to 5 of the drawings, there is provided an injector comprising an elongated body 4 formed with a pair of cylindrical end portions constituting, for the purpose of description, inner and outer portions 5 and 6, respectively. The outer portion 6 is of greater diameter than the inner portion 5, and is formed with a partition 7 defining outer fluid selecting and inner air receiving chambers 8 and 9, respectively. The outer end wall 10 of the chamber 8 is provided with fluid inlet apertures 11 while the partition is provided with air admitting openings 12.

The inner portion 5 is connected to a life raft R by means of a fitting 13 and is provided, adjacent to the fitting, with a check valve assembly 14 operable for permitting fluid to be introduced into said raft for inflating the same and in a manner hereinafter disclosed. Interiorly, the portion 5, is formed with a Venturi passage 15, communicating with the air receiving chamber 9 and the check valve assembly 14 whereby fluid is conveyed to the raft through said check valve assembly.

A nozzle 16 is coaxially mounted in the air receiving chamber 9 and is formed with a cylindrical intermediate portion 17 and with hemispherical and frustum-shaped ends 18 and 19, respectively, to define a streamlined body. The frustum-shaped end 19 is disposed towards the inner portion 5 and is provided with a discharge orifice 20 for directing fluid from the nozzle 16 into the Venturi passage 15.

The nozzle 16 has connected thereto, one end of a conduit or pipe 21, which extends through the injector and has its other end connected to a control head 22 of a container 23, the latter con-

taining a high pressure fluid medium, for instance, carbon dioxide. The control head 22 is of a well known construction and may be provided with the usual valve operating hand wheel 24 for effecting release of the fluid medium in the container whereby said fluid medium is discharged to the nozzle.

Disposed within the fluid selecting chamber is a selector valve mechanism (Figures 3, 4 and 5) comprising a disc 25 fixed to a shaft 26 rotatably journaled in the partition 7 and the end 18 of the nozzle. The disc 25 is formed with a plurality of air openings 27 controlled by valve members 28 slidably mounted in guideways 29 carried by the disc 25. The valve members are urged towards the shaft 26 by means of leaf-springs 30 mounted on the disc and which slidably engage pins 31 carried by the valve members, the latter being provided with weights 32 for actuating the valve members outwardly against the tension of the springs, to uncover the openings 27 in a manner hereinafter made apparent. The ends of the shaft 26 have fixed thereto rotors 33 and 33' operatively disposed in the chamber 8 and the nozzle 16, respectively.

In use, (assuming the life raft is launched in deflated condition upon the water and that the apertures 11 in the wall 10 are disposed above the water, and the fluid pressure medium is released from the container 23, by operation of the hand wheel 24) the fluid medium is introduced into the nozzle 16 and is discharged therefrom through the orifice 28 into the Venturi passage 15. As the fluid pressure medium is discharged into the Venturi passage 15, it draws air from the air receiving chamber 9 into the Venturi passage where it mixes with the pressure fluid medium to form a mixture, for instance, 50% air and 50% fluid pressure medium. This mixture is introduced into the life raft through the check valve assembly 14 and the fitting 13 and thus effects inflation of the life raft.

As the pressure medium flows through the nozzle 16, it operates the rotor 33' therein and thus effects rotation of the shaft 26 at relatively high speed due to the high pressure of the fluid medium. Rotation of the shaft 26 serves to rotate the disc 25 with the result that the valve members 28 are actuated outwardly with respect to the shaft 26 and against the tension of the springs 30 due to centrifugal force. When the valve members are actuated outwardly, they uncover the openings 27, thus establishing communication between the chambers 8 and 9 through the openings 12 and 27. Rotation of the shaft 26 operates the rotor 33 which, in this instance, serves to draw air into the chamber 8 through the apertures 11.

In the event that the injector is submerged and water enters the chamber 8 through the apertures 11, the rotation of the shaft 26 will be decelerated due to the water having a greater mass than air and acting upon the rotor 33. When the shaft 26 is thus decelerated, the valve members 28, under the influence of the leafsprings 30, will be centripetally operated with respect to the shaft 26 and close the openings 27 to preclude admittance of water into the chamber 9. When the openings 27 are closed, a larger volume of the fluid medium from the container 23 is utilized for 70 inflating the raft.

In Figures 6 and 7 modified injectors are illustrated. These injectors are adapted to be used in connection with, for example, a generally ring-shaped, bottomless flotation device, either side of

which may constitute the lower surface when the device is launched. The injector is positioned equidistantly between the upper and lower surfaces of the device to enable air from the atmosphere to enter the injector. Ordinarily, this position of the injector is above the water line, or is at least above the high water line. However, in some instances, due to heavy loading of the flotation device, the injector is frequently disposed below the load water line, thus cutting off the supply of air from the atmosphere for mixture with the fluid medium during inflation of the device.

In order to overcome this difficulty, and as illustrated in Figure 6 of the drawings, there is provided a selector valve mechanism comprising a tube 40 having upper and lower ends, and with the upper end being reversely curved to provide a valve portion 41 which is normally maintained above the longitudinal axis of the body 4 and the load water line. The valve portion 41 is provided with upper and lower chambers 42 and 43, respectively, and which chambers are separated by a valve seat 44. The lower chamber 43 is provided with a bottom wall 45 formed with openings 46 while the circumferential wall is provided with openings 47. Contained within the lower chamber 43 is a valve member 48, in this instance, a ball constructed of cork. The valve member 48 normally is disposed in spaced relation to the valve seat 44 to permit air from the atmosphere to enter the tube through the valve seat and the openings 46 and 47 when the portion 41 is disposed above the water.

Between the upper and lower ends, the tube 40 is provided with a laterally extending section 49 pivotally connected to the wall 10' of the portion 6 whereby air from the valve portion 41 is introduced into the air receiving chamber of the body. 40 The lower end of the tube 40 is closed by a weight 50 which functions to maintain the valve portion 41 above the body, regardless of which surface of the raft is submerged, whereby air may enter the selector valve mechanism.

Should the valve portion 41 become submerged during the operation of the device, water entering the lower chamber 43 through the openings 46 and 47 will cause the valve member 48 to be floated into closed relation with the valve seat 44 and thus preclude water entering the air receiving chamber of the section 6. When the valve portion 41 is disposed out of the water, the openings 46 serve to drain the water from the lower chamber 43, thus permitting unseating of the valve member 48.

In instances where relatively small containers are used for storing the carbon dioxide, the container may be utilized as a weight in lieu of the weight 50 disclosed in Figure 6. In a construction of this character, as illustrated in Figure 7, a container 59 is provided with a control head 60 equipped with a laterally disposed hand wheel 61 for operating the control head and with a fitting 62 secured within the lower end of the tube 40 and having connected thereto the lower end 63 of a pipe 64. The pipe 64 extends through the laterally extending section 49 and lower end of the tube 40 and has its other end 65 secured within the rear end or hemispherical portion of a nozzle 66, whereby fluid medium from the container 59 is conveyed through the nozzle 66 for discharge therefrom.

In the inflation of a flotation device by a stored high pressure fluid medium, approximating 1000 lbs. per square inch, it is necessary that

the medium be introduced into the device at a relatively low pressure ranging from a few ounces to a few pounds per square inch in order to preclude over-inflating. Heretofore, no advantage has been taken of the energy of the medium at high or relatively high pressure, with the result that considerable energy was wasted upon the reduction of the pressure to a low pressure. The invention permits the utilization of this previously wasted energy in a manner wherein it serves to draw in and mix air with the medium, thus, permitting the flotation device to be fully inflated with a mixture of pressure medium and air with a resulting low requirement in the amount of high pressure fluid medium initially necessary for the inflation.

From the foregoing, it will be apparent that this lower requirement permits the use of a relatively smaller and lighter container for its storage and if desired, a quantity of the medium may be retained in the container for future use after initial discharge.

As various changes may be made in the form, construction and arrangement of the parts herein, without departing from the spirit and scope of the invention and without sacrificing any of its advantages, it is to be understood that all matter herein is to be interpreted as illustrative and not in any limiting sense.

It is also to be understood that the following claims are intended to cover all the generic and specific features of the invention herein described, and all statements of the scope of the invention which, as a matter of language, might be said to fall therebetween.

I claim:

1. A device of the character described, comprising, a body provided with a fluid receiving chamber and formed with a Venturi passage communicating with said chamber and a receiver, a nozzle disposed in said chamber for discharging a fluid medium into said passage for mixture with a fluid of predetermined density, and means operable by the fluid medium for permitting the admittance of the fluid of predetermined density into said chamber to the exclusion of a liquid.

2. A device comprising a body formed with fluid receiving and fluid discharging portions and with the latter portion formed with a Venturi passage, means in said fluid receiving portion adapted to be connected to a source of fluid medium supply and arranged for discharging fluid from the supply into said passage in a manner to convey a fluid from said fluid receiving portion into said passage for mixture with the fluid medium discharged by said means, and means affected by liquid for controlling the fluid to be conveyed into said passage for mixture with said fluid medium.

3. In means for distending an inflatable flotation device, the combination of a fluid medium container, means for connecting said container to the flotation device and supplying the latter with fluid medium from said container and operable to provide for mixture of air with the fluid medium, and means affected by liquid for precluding the admittance of liquid for mixture with said fluid medium.

4. In a device for distending an inflatable flotation device, the combination of a fluid medium container, means for connecting said container to the flotation device for supplying the latter with fluid medium from said container, said means including selector means operable by the fluid medium for permitting introduction of air into said

connecting means for mixture with the fluid medium and operable upon the admittance of water into said connecting means for controlling the admittance of the water in a manner to preclude mixture with the fluid medium.

5. In means for distending an inflatable flotation device of normally deflated condition, the combination of high pressure fluid medium container means, an injector having an air inlet subject to submersion in water and provided for connection between said container means and the flotation device for supplying the latter with fluid medium from said container means, said injector including means providing for the introduction of air from the atmosphere into said injector through said inlet for mixture with the fluid medium and for precluding the admittance of water into said injector when said inlet is submerged, and means carried by said last mentioned means for normally maintaining the latter above said injector.

6. In means for distending an inflatable flotation device of normally deflated condition, the combination of high pressure fluid medium container means, an injector having an air inlet subject to submersion in water and provided for connection between said container means and the flotation device for supplying the latter with fluid medium from said container means, means movably connected to said injector providing for the introduction of air from the atmosphere into said injector through said inlet for mixture with the fluid medium and for precluding the admittance of water into said injector when said inlet is submerged, and weight means carried by said means for normally maintaining the latter above said injector.

7. In means for distending an inflatable flotation device normally in a deflated condition, the combination of a high pressure fluid medium container means, an injector having an air inlet subject to submersion in water and provided for connection between said container and the flotation device for supplying the latter with fluid medium from said container, and means pivotally connected to said injector and providing for the introduction of air from the atmosphere into said injector through said inlet for mixture with the fluid medium and for precluding the admittance of water into said injector when said inlet is submerged, said container being carried by said means and constituting a weight for normally maintaining said means above said injector.

8. Distending means for an inflatable flotation device, said means comprising container means for high pressure fluid, means including an injector for providing fluid communication from the container means to the flotation device and including means providing for the admission of air to said communication means, and fluid responsive means adapted to be actuated by said pressure fluid for urging the ingress of air to the injector.

9. Distending means for an inflatable flotation device, said means comprising container means for high pressure fluid, means including an injector for providing fluid communication from the container means to the flotation device and including means providing for the admission of air to said communication means, means including valve means for controlling said admission means, and means adapted to be actuated by said pressure fluid for actuating said valve means.

10. Distending means for an inflatable flotation device, said means comprising container means

for high pressure fluid, means including an injector for providing fluid communication from the container means to the flotation device and including means providing for the admission of air to said communication means, means including valve means for controlling said admission means, and means adapted to be actuated by said pressure fluid for actuating said valve means to open position and affected by liquid for closing said valve means.

11. Distending means for an inflatable flotation device, said means comprising container means for high pressure fluid, means including an injector for providing fluid communication from the container means to the flotation device and including means providing for the admission of air to said communication means, means including valve means for controlling said admission means, and means adapted to be actuated by said pressure fluid for urging the ingress of air to the injector and for actuating said valve means.

12. Distending means for an inflatable flotation device, said means comprising container means for high pressure fluid, means including an injector for providing fluid communication from the container means to the flotation device and including means providing for the admission of air to said communication means, means including valve means for controlling said admission means, and means adapted to be actuated by said pressure fluid for urging the ingress of air to the injector and for actuating said valve means to open position and affected by liquid for closing the valve means.

13. In combination, an inflatable flotation device, means for injecting an inflating fluid into the device having an inlet for entraining air with the inflating fluid, and means responsive to the immersion of said inlet into a flotation liquid for preventing the entrainment of the liquid.

14. In combination, an inflatable flotation device adapted for flotation in different operative positions, means having a passageway for injecting an inflating fluid into the device and including a portion having an inlet for entraining air with the inflating fluid, said portion being movable relative to said passageway to adjust said inlet according to said different positions, and means responsive to immersion of said inlet in a flotation liquid for preventing the entrainment of this flotation liquid.

15. In combination, an inflatable flotation device adapted for flotation in different operative positions, means having a passageway for injecting an inflating fluid into the device and including a portion having an inlet for entraining air with the inflating fluid, said portion being movable relative to said passageway to adjust said inlet according to said positions, means responsive to the positioning of the device in any of said different positions for effecting the adjusting movement of said inlet, and means responsive to immersion of said inlet in a flotation liquid for preventing the entrainment of this flotation liquid.

16. In combination, an inflatable flotation device adapted for flotation in different operative positions, means having a passageway for injecting an inflating fluid into the device and including a portion having an inlet for entraining air with the inflating fluid, said portion being movable relative to said passageway to adjust said inlet according to said different operative positions, gravity-responsive weight means including a container for said inflating fluid for effecting the adjusting movement of said inlet, and means responsive to immersion of said inlet in a flotation liquid for preventing the entrainment of this flotation liquid.
